UNITED STATES PATENT OFFICE.

ELBERT G. GRAVES, OF HOWARD, TEXAS.

DOUBLE-ROW-PLANTER CARRIAGE.

No. 833,831.

Specification of Letters Patent.

Patented Oct. 23, 1906.

Application filed December 18, 1905. Serial No. 292,323.

To all whom it may concern:

Be it known that I, ELBERT G. GRAVES, a citizen of the United States, residing at Howard, county of Ellis, and State of Texas, have 5 invented a Double-Row-Planter Carriage, of which the following is a specification.

This invention relates to improvements in planter-carriages, and particularly to means for regulating the spacing of two planters; 10 and the object is to improve the carriage shown in Letters Patent granted to me on November 6, 1900, No. 661,047. Other objects and advantages will be fully explained in the following description, and the invention will be more particularly pointed out in the claims.

Reference is had to the accompanying drawings, which form a part of this application and specification.

20 Figure 1 is a perspective view of the planter-carriage, parts of the frame being broken away. Fig. 2 is a plan view of the carriage-frame and the spacing and shifting mechanism. Fig. 3 is a perspective view of the carriage from the rear of the device. Fig. 4 is a 25 plan view of one of the shifting devices. Fig. 5 is a detail view of the frame for vertical adjustment and balancing of the planter; and Fig. 6 is a perspective view of the invention, 30 showing the planters attached.

Similar characters of reference are used to indicate the same parts throughout the several views.

A suitable truck, consisting of the axle 1, 35 wheels 2, and spindles having upwardly-bent shanks 3, to be attached to the axle 1 and forming with said axle an arched axle, is provided for mounting the double-row-planter carriage. The shafts 4, which are attached to the axle 1, the draft-beam 5, to which the shafts 4 are attached, and braces 6, attached to the axle 1 and to the shafts 4, 40 constitute the main supporting-frame. Additional frame portions consist of the depending uprights 7 and 8, attached to the draft-beam 5, and braces 9 and 10, attached to the axle 1 and to the uprights 7 and 8. A cross-bar 11 is attached to the braces 9 and 10. Braces 13 and 14 are attached to the outside 45 of uprights 7 and 8, respectively, and to the shanks 3 of the truck-spindles. The above-described elements constitute the principal framework of the device.

The planters, which are to be of any ordinary design, such as are found on the market,

are carried and supported by two elements—shiftable carriers 16 and 17 and balancing-supports 18 and 19. The carriers 16 and 17 are mounted on sleeves 20, (see Fig. 4,) which are supported on rods 21, carried by uprights 60 7 and 8. The carriers are mounted loosely on the sleeves 20, so that the carriers are shiftable laterally between each pair of uprights 7 and 8. The carriers are provided with suitable arms 22, to be attached to the arms 65 or beams projecting in front of the planter. Means are provided for shifting and spacing the carriers 16 and 17. Levers 23 and 24 are fulcrumed on the cross-bar 11, and the lower ends are connected loosely with the carriers 70 16 and 17, respectively, by means of eyebolt-couplings 25 and braced connections 26, which engage the couplings 25, one connection 26 being attached to carrier 16 and one connection 26 being attached to carrier 17. 75 A rack 27 is attached to braces 9 and 10. Each of the levers 23 and 24 carries a connecting-rod 28 and spring-actuated detent 28', adapted to engage the rack 27 at various 80 adjustments. The detents 28 may be actuated by a thumb-lever 29, located adjacent to the grip of each lever. By means thus described the carriers 16 and 17 can be shifted to space the same at any desirable position to the right or left or toward or from each 85 other.

The balancing-supports 18 and 19 are each provided with arms 30, connected thereto by links 31. The arms 30 are to be attached to the arms or beams of the planters between 90 the planters and supporting-wheels 45 for the purpose of raising the planters to be shifted. The supports 18 and 19 are each connected to levers 32 by links 33. The levers 32 are fulcrumed on the shafts 4 and carry spring-actuated detents 34, which engage racks 35, which are attached to the shafts 4. The detents are actuated by thumb-levers 36, which are mounted on the levers 32 adjacent to the grips thereof. By means of the levers 32 the supports may be elevated or lowered and held at any desirable position for the purpose of adjusting the planters laterally to the desired positions. The planters will be supported by the balancing-bars 18 and 19, so 95 that the planters will be carried in their proper upright positions when shifted laterally by the spacing and shifting means herefore described and will not be tilted or shifted to lateral positions.

The I-bolt couplings 25 have reduced rounded portions 37, which permit rocking movement of the carriers 16 and 17, and the flat portions of the couplings are perforated 5 to receive rivets 38, which connect the levers 23 and 24 to the couplings. The levers 23 and 24 have slots therein to permit freedom of movement of the levers as the lower ends of the levers move through arcs of circles for 10 shifting the carriers 16 and 17.

A suitable seat 39 is mounted on the truck, and a foot-rest 40 is provided and attached to the truck by hangers 41, which are attached to the seat-bar 43, and by braces 42, which 15 are attached to braces 9 and 10.

Various changes may be made in the construction of the various parts composing the planter-carriage without departing from my invention.

20 Having fully described my invention, what I claim as new, and desire to secure by Letters Patent, is—

25 1. A double-row-planter carriage comprising a suitable truck, shiftable carriers mounted on said truck, means for laterally shifting said carriers, and means for balancing planters carried by said carriers in different positions.

30 2. A double-row-planter carriage comprising a suitable truck, shiftable carriers mounted on said truck, means for laterally adjusting said carriers, and means for balancing and vertically adjusting planters mounted on said carriers.

35 3. A double-row-planter carriage comprising a suitable truck, carriers mounted on said truck, means for shifting and spacing said carriers laterally, means for holding said carriers in their shifted positions, and balancing 40 attachments for permitting planters supported by said carriers to balance themselves at various positions to which said carriers may be shifted.

45 4. A double-row-planter carriage comprising a suitable truck, hangers attached to said truck and carrying bearings at the lower ends thereof, carriers slideable on and pivotally engaging said bearings, means for holding said carriers in various positions on said bearings, 50 balancing attachments coöoperating with said carrier for supporting planters, and means for vertically adjusting said balancing attachments.

5. A double-row-planter carriage comprising

ing a suitable truck, hangers attached to said 55 truck and carrying bearings in the lower ends thereof, carriers slideable on and pivotally engaging said bearings, means for shifting and holding said carriers in various positions on said bearings consisting of levers fulcrumed 60 on said truck and loosely connected to said carriers, a rack attached to said truck, spring-actuated detents carried by said levers for engaging said rack, and balancing attachments coöperating with said carriers for sup- 65 porting planters.

6. A double-row-planter carriage having a suitable truck, hangers rigidly attached to said truck and carrying bearings in the lower ends thereof, carriers slideable on and pivotally engaging said bearings, levers fulcrumed 70 on said truck for shifting and spacing said carriers laterally, a rack mounted on said truck, spring-actuated detents carried by said levers to engage said rack whereby said 75 carriers are held in whatever positions they may be shifted, and means coöperating with said carriers for supporting planters.

7. A double-row-planter carriage having a suitable truck, shiftable carriers mounted on 80 said truck, and balancing attachments coöperating with said carriers for supporting planters and permitting planters to balance themselves in different positions to which said carriers may be shifted.

8. A double-row-planter carriage having a suitable truck, shiftable carriers mounted on said truck, balancing attachments coöperating with said carriers to support planters, levers fulcrumed on said truck and carrying 90 said balancing attachments, racks attached to said truck, and spring-actuated detents carried by said levers for engaging said racks whereby said balancing attachments may be held at various vertical adjustments. 95

9. A double-row-planter carriage comprising a suitable truck, shiftable carriers mounted on said truck, levers for shifting said carriers and holding at various adjustments, and I-bolt couplings connecting said levers and 100 said carriers.

In testimony whereof I set my hand, in the presence of two witnesses, this 28th day of November, 1905.

ELBERT G. GRAVES.
